(57) **CLAIM**

The ornamental design for a twin foot pedal control, as shown and described.

DESCRIPTION

FIG. 1 is a perspective view of the twin foot pedal control showing my new design;

FIG. 2 is a rear view of the twin foot pedal control of FIG. 1;

FIG. 3 is a front view of the twin foot pedal control of FIG. 1;

FIG. 4 is a right side view of the twin foot pedal control of FIG. 1;

FIG. 5 is a top view of the twin foot pedal control of FIG. 1; and,

FIG. 6 is a bottom view of the twin foot pedal control of FIG. 1.

The broken lines in FIGS. 1, 2, 5, and 6 are illustrative of environmental structure only and form no part of the claimed design.
